[57] CLAIM

The ornamental design for a wearable airplane toy, as shown and described.

DESCRIPTION

FIG. 1 is a perspective of a wearable airplane toy showing my new design, the figure shown in broken lines for illustrative purposes only;

FIG. 2 is a front perspective view thereof;

FIG. 3 is an exploded perspective view thereof;

FIG. 4 is a left side view thereof, the right side being a mirror image and the propeller removed for ease of illustration;

FIG. 5 is a bottom plan view of FIG. 4; and,

FIG. 6 is a rear elevational view of FIG. 4.
